HENRI JEAN JOSEPH MARIE DE REGNAULD DE BELLESCIZE, OF PARIS, FRANCE

OSCILLATION CONTROL

Application filed March 10, 1923, Serial No. 624,286, and in France March 29, 1922.

The present invention has for its object to reduce the effect of atmospheric disturbances on wireless telegraph and telephone receivers.

5 It has already been suggested for this purpose to associate with receiving circuits an element such as an electron tube or a rectifier contact which is suitably de-sensitized or also a suitably controlled microphonic contact. 10 Under these conditions such element does not interfere with the receiving of the signals but operates under the control of the disturbances either for compensating the disturbing current which would result in the indicating apparatus or for rapidly damping the resulting oscillations.

The present invention has for its object to provide a system of this character. The invention is characterized by the association of 20 a three-electrode relay tube with the resonator in which it is desired rapidly to damp the disturbing oscillations. The association or combination is such that the plate-filament space of the tube is in shunt between two 25 suitably selected points of the resonator, a suitable, usually feeble, potential difference being in series with said space. Said space performs the function of a variable resistance for the damping because, in accordance with 30 the present invention, the grid of the tube is connected, preferably through a current source with a point of the receiving circuit which is selected in such a manner that under the control of the disturbances to be damped 35 it presents a positive rise of suitable value of its mean potential difference with respect to the filament of the tube in question.

Obviously, the invention may be subjected 40 to various modifications. It is possible to apply it a number of times within one and the same receiving station, i. e. to provide a plurality of damping tubes each having for its function the damping of one or a plurality of 45 resonant circuits of the station, and this in combination with the control of all the grids by varying the potential of one point, etc. Finally under certain circumstances, the arrangement may be completed by combining 50 it with other anti-atmospheric arrangements

and more particularly with limiting arrangements.

The invention will be more readily understood with the aid of the following description and enclosed drawings which exemplify 55 a few embodiments of the present invention, in which

Fig. 1 shows certain apparatus explaining the principles of my invention,

Fig. 2 shows curves explaining the operation of my invention,

Fig. 3 shows an arrangement according to my invention in which a three-electrode tube controls the damping in a resonant circuit,

Fig. 4 shows an arrangement in which a 65 plurality of resonant circuits are utilized,

Fig. 5 shows an arrangement wherein the plurality of resonant circuits are arranged as a filter,

Fig. 6 shows an alternative modification 70 for controlling the damping tube, and

Fig. 7 shows still another modification for the same purpose.

The principle consists in this; rapidly to 75 damp all oscillations which are stronger than the signal by associating a few of the receiving resonators with an equal number of resistances the value R of which depends on the amplitude of the oscillations. This association is schematically illustrated in Fig. 80 1 in which a variable resistance R is connected with the terminals of condenser C . The damping factor will be $\frac{r}{2L} + \frac{1}{2RC}$ of which

$\frac{r}{2L}$ is that of resonator LC , and the other 85

$\frac{1}{2RC}$ is due to the damping resistance R . The element constituting this resistance must be such that its value R be practically infinite in the normal service and drop to as low a value as possible as soon as under the control of e. g. an aperiodic disturbance the resonator becomes the seat of an oscillation having an 90 amplitude which is considerably larger than that of the signal.

In practice the variable resistance R is composed of the plate-filament circuit of a three-electrode tube, the grid potential, of 100

which is controlled by the amplitude of the oscillations received. The curves illustrating the plate current J as a function of weak positive and negative values of the plate potential U , have the form shown in Fig. 2. 5 The characteristic merges with the abscissa ($j=0$) when the grid potential v is slightly negative and will rapidly increase as soon as this potential v increases. Assuming that the mean potential of the plate is adjusted to 10 a certain value U_0 , the internal resistance R of the plate filament circuit will be infinite when the grid potential v will be equal or inferior to v_0 ; for grid voltage $v=v_2$ this resistance will have the following finite 15 value:—

$$R = \frac{OU}{OJ} = \frac{1}{\tan \alpha} = \cot \alpha$$

20 The association of a resonator LC with a tube T adapted to serve as a damping device is schematically illustrated in Fig. 3. The plate and filament of the tube T constitute the resistance R and are respectively connected with the plates of the condenser C. By means 25 of a wiper D the mean plate potential may be adjusted to a suitable value U^0 . The oscillations are rectified by means of any suitable detector as for example the tube Y having 30 in its grid circuit a condenser P shunted by a resistance Q. They will cause the diminution of the mean current in the resistance H inserted in the plate circuit of the tube Y and therefore an increase of the mean potential of this plate. This increase is transmitted 35 to the grid of the tube T through the agency of a current source S^4 adjusted to such a value that under the control of a signal the potential v of this grid will attain the value v^0 for which the resistance R will cease to 40 be infinite. In practice this result is obtained by reducing the number of cells in the battery S^4 until the intensity of the signal tends to weaken.

45 Fig. 4 illustrates a plurality of resonators $L^1 C^1 - L^2 C^2 - L^3 C^3$ all connected with tubes T^1, T^2, T^3 . It is advisable to provide means for preventing the return to the first amplifying stages of high frequency currents 50 which pass through the detector. This is accomplished by means of a certain number of filtering circuits $M^1, C^4 - M^2, C^5$ which comprises self inductions M^1, M^2 and capacities C^4, C^5 opposing the rectified currents by 55 reactances which are practically equal to the internal resistance of the detector tube. The batteries S^1, S^2, S^3 bring the grids of the amplifying tubes to suitable potentials, which are usually slightly different from U^0 which 60 is the potential of the plate of tube T.

The present arrangement is particularly adapted for receiving very long waves. It may be combined to good effect with a limiting means X whereby disturbing oscillations 65 which occur in the listening apparatus G

will be reduced in their duration and will be limited in their amplitude.

The grouping and nature of the resonators to be damped may be as desired. An open or a closed antenna may be used, or a group of antennæ may be used for the purpose of improving the direction of the receiver. 70

75 Fig. 5 exemplifies an open antenna $L^1 C^1$ actuating any desired number of closed resonators L^2, C^2, L^3, C^3 , etc. associated with each other in a manner to constitute a filter. All these circuits are respectively connected with the plates and the filaments of the damping tubes T^1, T^2, T^3 , etc. the grids of which are subjected to variations of potential produced in the resistance R by the oscillations rectified in the detector tube D.

80 A source B serves for bringing to a suitable negative value the potential at point O from which the grids of the tubes T^1, T^2, T^3 etc. are controlled.

85 A system composed of self inductions M and capacities N prevents the passage of high frequency oscillations which traverse the detector D towards the tubes T^1, T^2, T^3 , etc.

90 A high frequency amplifier A of any suitable type or strength may precede the detector D.

95 Any well known registering apparatus G may be used.

100 By means of suitable connections invariable relative potentials will be maintained at the different sources S^1, S^2, S^3 , etc. from which current is supplied to the tubes.

Furthermore, the functioning of the receiving oscillations on the grids of the damping tubes T^1, T^2, T^3 , etc. may be varied.

105 In the example shown in Fig. 5, the operation is the same as that previously described.

Fig. 6 represents a circuit arrangement in which the oscillations rectified by detector tube D act on the grids T^1, T^2, T^3 , etc. (a single triode damping tube is shown for the sake of simplicity) through the agency of a transformer K. Instead of the oscillations being translated always by a positive variation of the potential common to the grid T^1, T^2, T^3 , etc. as was the case in the circuit arrangement shown in Fig. 1, the oscillations are translated by positive and negative alterations, only the former of which produce the desired damping effect. Notwithstanding this the arrangement is sufficiently efficacious. The circuit shown in Fig. 6 is well adapted for receiving by means of a heterodyne E and a telephone H. 115

120 Fig. 7 shows a circuit arrangement in which the point O controlling the grids of tubes T^1, T^2 is located ahead of the detector D. Therefore the high frequency oscillations if sufficiently strong will cause themselves their damping. In this case the amplification that exists between points O and the first one L^1, C^1 of the damping resonators must be slight, because otherwise the re- 125

ceiver would become the seat of autoenergization phenomena.

Having described my invention, what I claim is:

- 5 1. In a receiving system, a pair of three-electrode tubes, a common resonant circuit connected to the grid-filament circuit of one of said tubes and to the plate-filament circuit of the other, and grid biasing means connected in the plate-filament circuit of the first tube to the grid of the second. 70
- 10 2. In a receiving circuit, a three-electrode tube having a tuned input circuit and an output circuit, and a second three-electrode tube having its plate and filament electrodes connected to said input circuit and its grid connected with the output circuit of said first tube. 75
- 15 3. In a receiving system, a detector, a resonant circuit connected to the input electrodes of said detector, and means for controlling the damping factor of said resonant circuit, comprising a thermionic valve having its plate-filament circuit connected to said resonant circuit and its grid connected to the detector output circuit. 80
- 20 4. In a receiving system, a detector, a resonant circuit connected to the input electrodes of said detector, and means for controlling the damping factor of said resonant circuit, comprising a thermionic valve having its output circuit connected in shunt to said resonant circuit and its grid connected through a current source to the output circuit of said detector. 85
- 25 5. In a receiving circuit, a resonant circuit, a three-electrode tube having its input electrodes connected to said circuit, a second three-electrode tube having its plate-filament electrode also connected to said resonant circuit, the plate-filament space of said second named tube acting as a variable resistance, and means connected between the output circuit of said first tube and the grid of said second tube to automatically control the potential on said grid and thereby the space resistance in accordance with oscillations in the resonant circuit. 90
- 30 6. In a receiving arrangement, a pair of three-electrode tubes, a common resonant circuit connected in the input circuit of one of said tubes and in the output circuit of the other, and a connection between the output circuit of the first and the grid of the second through a biasing battery in a manner such that the positive potential of said battery is impressed on the plate of the first tube and a predetermined or adjustable negative potential on the grid of the second. 95
- 35 7. The combination with a resonant circuit, of a first three electrode tube having its plate-filament circuit connected in shunt with said resonant circuit, a second three electrode tube having its grid circuit connected to said resonant circuit, a grid biasing means connected to the plate-filament circuit of said second tube, and a connection between said last mentioned means and the grid of said first tube. 100
- 40 8. The combination with a resonant circuit, of a three-electrode tube having its plate-filament circuit connected in shunt to said resonant circuit, a second three-electrode tube having its grid-filament circuit connected to said resonant circuit and a connection between the grid of said first tube and the plate-filament circuit of said second tube. 105
- 45 9. The combination with a resonant circuit, of a three-electrode detector tube having its input circuit connected to said resonant circuit, a second three-electrode tube having its plate-filament circuit connected in shunt to said resonant circuit, a grid biasing means connected to the plate-filament circuit of said second named tube, and a connection between the grid of said second named tube and the output circuit of said detector tube through said grid biasing means. 110
- 50 10. The combination with a resonant circuit, of a three-electrode detector tube having its input circuit connected thereto, a source of energy having its positive pole connected to the output circuit of said tube, a second three-electrode tube having its plate-filament circuit connected in shunt to said resonant circuit, means in said plate-filament circuit for impressing a desired potential on said plate, and a conductor connected between the grid of said second named tube and a predetermined negative potential point of said source of energy. 115
